METHOD OF APPLYING PROTECTIVE COLORING IN THE PRINTING OF DOCUMENTS REPRESENTING VALUE

Sydney George Clifford, London, England, assignor to Waterlow & Sons Limited, London, England, a British company

Application August 2, 1934, Serial No. 738,137
In Great Britain August 9, 1933

9 Claims. (Cl. 101—211)

This invention relates to an improved method of applying protective coloring in the printing of documents representing, or intended to represent, value, such, for example, as bonds, share warrants, bills, notes, cheques and the like and has for its object to render same as difficult of fraudulent reproduction as possible.

It has been customary to employ for this purpose one, or a combination of two or more colors, chosen to produce protective antiphotographic tints, that is to say tints which underlie the main printing of the document and are of such a color or nature that they cannot be photographically separated from the main printing for the purpose 15 of making a fraudulent imitation of the document.

As an additional safeguard a somewhat intricate pattern has been employed, which is applied in a succession of two or more printings in close 20 register, each printing being preferably a different color.

In multi-color printing work, where the ink in the duct, leading to the roll which feeds the inking roller, is divided into separate colors, a merging 25 of the bands of colors can be produced, regulated and determined by the amount of lateral oscillating movement of the inking mechanism, the result being to produce a "rainbow" effect.

According to this invention there is employed 30 in the printing of a document, which is to be rendered as fraud-proof as possible the method of applying a protective anti-photographic pattern to a part (or parts) of the document by a first printing operation employing two or more bands 35 of colors and subsequently applying, by means of a second printing operation, a further pattern to another part or parts of said document, the two printings being in close register in such a way as to form a substantially continuous pattern, whilst 40 the bands of colors are discontinuous.

The invention moreover embraces the method of applying protective colorings to documents consisting in subjecting the sheet of paper to two successive printing operations, whereby a substantially continuous pattern is applied to the paper by the two impressions, each impression comprising two or more bands of color merging at their edges, the bands of colors of the first impression being substantially discontinuous with 45 respect to the bands of colors of the second impression.

One method of printing a document in accordance with the invention consists in applying a close register pattern to a sheet in two impressions, each formed by a printing block inked with 50

two or more bands of colors merging at their edges, a part (or parts) of the document being printed by one block and the remainder (or part of the remainder) of the document being printed by the other block, the two impressions being in close register with one another without any overlapping, whilst the bands of colors of the two impressions are substantially discontinuous.

The term "printing block" used in this specification is to be construed as meaning any printing element, such as a printing block or litho-plate.

One embodiment of this invention is illustrated, merely by way of example, in the accompanying drawing:—

Figs. 1 and 2 show the separate impressions obtained from two printing plates A and B respectively and

Fig. 3 illustrates the combined impressions produced by the two plates A and B.

In order to make the description clear, the anti-photographic tint or pattern is represented by a series of circles, it being understood however that the pattern would be an intricate one composed of fine and numerous characters or lines, same underlying the main printing of the document, 23 which is not shown in the drawing. It will be assumed that the desired pattern is obtained by two printings produced by the plates A and B, but if desired more than two printing operations may be employed.

The plate A produces an impression on a part of the document, the ink in the duct being divided into three bands namely, blue, red and blue. By giving an oscillating movement to the rollers feeding the ink to the inking roller, a merging of 35 the colors is brought about in such a way as to produce a rainbow effect, which operation is commonly known as "rainbowing."

The colors in the drawing are shown according to the heraldic convention, and as it is not possible to illustrate the rainbow effect in black and white, this is diagrammatically illustrated by the brackets *a a* and *b b*. It is pointed out however that the merging or rainbow effect is a gradual one, and that there is no hard and fast line of 45 division between the bands of colors.

Fig. 2 shows the impression produced on a sheet of paper by plate B using three bands of colors, namely green, purple, and green, which are rainbowed as shown diagrammatically by the brackets *c c* and *d d*.

It will be observed that in Figs 1 and 2 certain portions 2 of the impression have no pattern, same being merely stippled with an appropriate color in order to constitute a background for that 55

part of the main printing of the document, such for example as a portrait, which could not suitably be applied on top of the anti-photographic pattern. This stippling however forms no part 5 of the present invention.

Assuming now that a sheet of paper shown in Fig. 1, which is produced by plate A, is subjected to a second printing operation by plate B in close register with the first impression, the result 10 shown in Fig. 3 will be obtained. It will be seen that the pattern produced by the two impressions is substantially continuous, the two meeting one another in close register along the lines 3 whilst the rainbowing effect or bands of color 15 are substantially discontinuous.

Thus in effect it will be seen that the sheet of paper is subjected to successive printing operations, each impression producing per se a relatively spaced or disjointed pattern with two or more merging bands of colors, whilst the sum of the two or more impressions results in the production of a substantially composite pattern in close register without overlapping in such a way 20 that the bands of colors of one impression are discontinuous with respect to the bands of colors of the other impression or impressions.

A document printed in accordance with this invention presents an attractive appearance, and moreover makes it very difficult to produce a 25 fraudulent reproduction.

What I claim and desire to secure by Letters Patent is:—

1. The method which comprises printing a background pattern upon a portion of a paper in a plurality of bands of diversified colors, and printing a background pattern upon an adjacent portion of the paper in close register with the pattern of the first printed portion and in bands of diversified colors contrasting with the bands of color of the first printing along at least a portion of adjacent edges of the respective printed portions.

2. In the printing of a background coloring upon paper, the process which comprises printing a pattern upon a portion of the paper in a plurality of bands of diversified colors, and printing a pattern upon adjacent portions of the paper in close register with the pattern of the first-printed

portions and in a plurality of color bands which each contrast with the contiguous portions of the color bands of the first printed portions.

3. In the printing of a fraud-preventing background pattern upon paper, the process which 5 comprises printing a pattern upon portions of the paper in a plurality of bands of color, and printing a pattern upon other portions of the paper in close register with the pattern of the first printed portion and in a plurality of bands 10 of color that are discontinuous with the bands of color of the first printed portions.

4. A printing process as claimed in claim 3, wherein the bands of color of at least one of said printings merge at their edges. 15

5. The process of printing a close register background pattern upon paper in two impressions which comprises printing the pattern upon spaced portions of the paper in bands of color, and printing the pattern upon adjacent non-overlapping 20 portions of the paper in bands of color contrasting with the pattern color at the adjacent edges of the first printed portions.

6. A process as claimed in claim 5, wherein the bands of color of both printings are all parallel to each other. 25

7. A process as claimed in claim 5, wherein the bands of color of at least one of the printings merge into each other.

8. A process as claimed in claim 5, wherein each band of color of one printing contrasts with each band of color of the other printing.

9. A sheet of paper for use in the printing of documents, said sheet of paper having a background design of small pattern elements extending continuously over an extended area of one side of the sheet, the extended area comprising a plurality of portions in each of which the pattern elements are arranged in bands of different colors, the pattern elements of each two adjacent portions being in close register to form component parts of a single substantially continuous background design and the coloring of the pattern elements being discontinuous along at least 40 a part of the junction of the said adjacent portions. 45

SYDNEY GEORGE CLIFFORD.
